(57) **CLAIM**

The ornamental design for a storage rack, as shown and described.

DESCRIPTION

FIG. 1 is a front top perspective view of the storage rack showing my new design;

FIG. 2 is a rear bottom perspective view thereof;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is an enlarged detailed view of portion 9 in FIG. 1;

FIG. 10 is an enlarged detailed view of portion 10 in FIG. 2;

FIG. 11 is an enlarged detailed view of portion 11 in FIG. 3;

FIG. 12 is an enlarged detailed view of portion 12 in FIG. 4;

FIG. 13 is an enlarged detailed view of portion 13 in FIG. 5;

FIG. 14 is an enlarged detailed view of portion 14 in FIG. 6; and,

FIG. 15 is a perspective view of a storage rack shown in an environment of use in an assembled position.

The dot-dash broken lines illustrate the border of the enlarged detailed views and form no part of the claimed design. The evenly dashed broken lines show environment that forms no part of the claimed design.

1 Claim, 15 Drawing Sheets
